(57) **CLAIM**

The ornamental design for a hay bag with windows for ventilation as shown and described.

DESCRIPTION

FIG. 1 is a front, right side perspective view of a hay bag with windows for ventilation of my new design;

FIG. 2 is a front elevational view of a hay bag of FIG. 1; FIG. 3 is a rear elevational view of the hay bag of FIG. 1; FIG. 4 is a right-side elevational view of the hay bag of FIG. 1, the left-side being a mirror image thereof;

FIG. 5 is a top plan view of the hay bag of FIG. 1; FIG. 6 is a bottom plan view of the hay bag of FIG. 1; FIG. 7 is a right-side elevational view of the hay bag of FIG. 1, with the window cover raised to show the mesh window, the left-side being a mirror image thereof when the window cover is raised;

FIG. 8 is a front, right-side perspective view of the hay bag of FIG. 1, with the window cover raised to show the mesh window; and,

FIG. 9 is an enlarged view of a portion of FIG. 8. The broken lines depict exemplary portions of the hay bag with windows for ventilation that are not claimed.

1 Claim, 8 Drawing Sheets
